UNITED STATES PATENT OFFICE.

SAMUEL C. HOEY, OF WILKINSBURG, PENNSYLVANIA, ASSIGNOR TO WESTINGHOUSE ELECTRIC & MANUFACTURING COMPANY, A CORPORATION OF PENNSYLVANIA.

APPARATUS FOR DIE CASTING.

Application filed July 13, 1923. Serial No. 651,221.

To all whom it may concern:

Be it known that I, SAMUEL C. HOEY, a citizen of the United States, and a resident of Wilkinsburg, in the county of Allegheny and State of Pennsylvania, have invented a new and useful Improvement in Apparatus for Die Casting, of which the following is a specification.

My invention relates to pressure casting devices, more especially to a device for casting rotors for dynamo electric machines.

It is among the objects of my invention to provide a device which shall be of simple, compact and inexpensive construction which shall be adapted to the casting of metal bodies of uniform quality and in production quantities.

In the process of die casting, which is a method of casting molten metal under pressure in a die or mold of the shape and contour of the body to be formed, the metal is usually contained in a reservoir associated with the die or mold with communicating openings or ports provided to permit the flow of the metal into the die. The ports may consist of one or more constricted openings depending upon the structure to be cast and the openings are ordinarily straight passages to offer the least resistance to the flow of the molten metal.

I have found that in casting bodies of irregular cross-section, such as squirrel cage rotors for dynamo-electric machines, the shape of the ports governs the quality of the casting in that the shape of the openings regulates the disposition of the molten metal as it is forced into the die or mold.

In squirrel cage rotors which consist of slotted laminations having conductor bars extending through the slots and united by end rings, the forming of the conductor bars by pressure casting prevents perfect formation of the end ring farther from the ports or openings due to the air and gases which are trapped in the mold by the incoming metal.

My present invention is directed to a device having specially shaped ports which retard the velocity of the fluid metal to effect a uniform rising thereof that forces the gases and air out through the vents at the top of the mold and permits of forming a

full end ring with a minimum amount of blow-holes or other irregularities in the casting.

In the accompanying drawing constituting a part hereof and in which like reference characters designate like parts,

Fig. 1 is a vertical cross-sectional view of a pressure casting device embodying the principles of my invention,

Fig. 2 is a cross-sectional view of a base plate utilized in the die or mold of the device shown in Fig. 1, and

Fig. 3 is a bottom plan view of the base plate.

Referring to Fig. 1, the pressure casting device therein illustrated comprises a mold or die consisting of a matrix 1 of ring shape that is mounted upon a base 2 comprising a reservoir or chamber 3 having a piston member 4 disposed therein. A baffle wall 5, provided with a central opening 6, is located intermediate the mold 1 and reservoir 3. A base plate 7 having a plurality of spiral ports 8 and a central recessed portion 9 is disposed in the mold 1 on top of the wall member 4 in central alinement with the opening 6. A clamping plate 10 is secured to the matrix 1 by a plurality of bolts 11. The base portion 2 is provided with openings 12 by which it may be clamped to a bed or work table as desired.

The operation of this device is briefly as follows: A rotor 13 comprising a plurality of superposed sheet iron laminations is assembled and secured in the matrix 1 between the base plate 7 and the clamping plate 10 in the manner shown in Fig. 1. The reservoir 3 is filled with molten metal, such as copper, aluminum, an aluminum alloy or the like and the piston 4 is actuated to cause the metal to advance against the baffle plate 5, forcing the metal through the central opening 6 into the recess 9 of the pressure plate 7 and through the spiral ports 8 into the matrix 1. The metal then slowly and uniformly rises filling up the space 15, the slots 16 and the space 17, forcing out any gases or trapped air through the vent holes 18 provided in the clamping plate 10. The spiral openings 8 function to effect a uniform rising of the metal in the matrix which prevents the trapping of air or gases in the

body, thus producing a casting having a homogeneous structure throughout. The spaces 15 and 17 receive metal to constitute the end rings and the slots 16 receive metal for the conductor bars of the cast body, which constitutes a rotor of integral structure.

If vertical ports in alinement with the portions to be cast, as is ordinarily used in pressure devices, were used, the metal would fill the spaces in an irregular manner so as to produce trapped air pockets and other irregularities in the casting. It is evident from the foregoing description of my invention that a pressure casting device such as is described herein may be utilized in casting bodies of special shapes in an efficient and expedient manner and that such a device is especially adapted to cast the end rings and conductor body portions of squirrel cage rotors of dynamo-electric machines.

Although I have described a specific embodiment of my invention, it will be obvious to those skilled in the art that the general design and proportions of the device illustrated herein may be varied and the number and shape of the ports may be changed without departing from the spirit of my invention.

I claim as my invention:—

1. A pressure casting device comprising a mold, a reservoir associated therewith, a baffle wall intermediate said mold and reservoir having radial communicating ports and

means for emptying the contents of the reservoir through said ports.

2. A pressure casting device comprising a mold, a reservoir associated therewith, a baffle wall intermediate said mold and reservoir, said wall having a central opening and a plurality of spiral ports communicating therewith.

3. A pressure casting device comprising a mold, a reservoir associated therewith, a baffle wall intermediate said mold and reservoir having a central opening therein, and a base plate in said mold disposed above the opening of said wall having a plurality of spiral ports communicating with the said opening.

4. A pressure casting device comprising a mold that is adapted to receive a body in or about which a casting is to be formed, a base plate for said mold having a plurality of spiral ports formed therein and means for filling the mold through said ports.

5. A pressure casting device comprising a mold and a reservoir associated therewith and means for discharging a liquid from said reservoir into said mold at a constant velocity, said means comprising a plurality of spiral ports and a pressure actuated piston.

In testimony whereof, I have hereunto subscribed my name this 2nd day of July, 1923.

SAMUEL C. HOEY.
